UNITED STATES PATENT OFFICE

MAX H. GOLDMAN, OF CHICAGO, ILLINOIS

SELF-ADJUSTING COLLAR BUTTON

Application filed January 6, 1932. Serial No. 584,991.

My invention relates to improvements in collar buttons, and its object is to provide a self-adjusting collar button formed of a single length of spring metal and having a head and a base, and a shank coiled to form a connecting post which is relatively rigid or solid to permit insertion through the buttonholes of the collar and neck band and to provide the desired connection, and which shank at the same time is self-extensible and self-retractable to permit use of the button at the front or back of the neck band or with any other different collar and neck band thicknesses without protrusion or discomfit.

The invention is illustrated in the accompanying drawing, in which:

Figure 1 is an enlarged side elevational view of a button embodying my invention; 20 Figure 2 is a plan view of the button shown in Figure 1;

Figure 3 is a longitudinal sectional view taken on the line 3—3 of Figure 2;

Figure 4 is a view showing the button at 25 the back of a neck band with the extensible shank in retracted position; and

Figure 5 is a view similar to Figure 4, showing the button at the front of the neck band with the shank extended to accommodate the greater collar and neck band thicknesses at that position.

In carrying out my invention I employ a single piece of spring-wire 5, which, in the illustrated embodiment of the invention, is 35 coiled to form the shank or post 6 with a relatively large base 7 at one end and a head 8 at the opposite end.

The turns or convolutions of the base 7 may be of spiral form disposed in a single plane with one end 9 of the wire at the outer edge of the base 7, as shown. Of course, the base coil may be laid in slightly conical form to raise the center of the base above the plane of the outer base edge, and other shapes 45 may be adopted than that selected for illustration.

The turns or convolutions of the stem 6 are of generally helical form continuing upwardly from the central part of the base 7 in a direction generally normal to the plane

of the base. The stem 6 is generally cylindrical in the illustrated embodiment, but it may be of conical form with the wider end at the bottom and the smaller end at the top. The spring wire preferably is relatively heavy, and the shank 6 is normally retracted with the convolutions of the shank 55 yieldingly pressing together one tightly upon the other, as shown in Figure 1.

At the upper end of the stem 6 the wire is 60 coiled spirally at 10 in a plane generally parallel the plane of the base 7, and from the outer end of the coiled part 10 the wire is coiled upwardly at 12 to form the head 8. The head 8 preferably is relatively small to 65 permit the same to pass more readily through the buttonholes in the collar and neck band of the shirt. It may be of generally tapered or upwardly rounded form, as shown, but it is to be understood that the configuration of 70 the head too may vary within the scope of my present invention. Preferably, upon completing the head 8, the head end of the wire is turned in at 14 through the interior of the head and down into the coiled shank 6. 75 The end of the extending end 14 of the wire terminates short of the base 7, and the disposition of this extending end 14 through the interior of the shank 6 preferably strengthens and aids in imparting rigidity 80 or stiffness to the shank 6, particularly in a lateral direction. Although the shank 6 is yieldable longitudinally for elongation and shortening of the distance between the base 7 and head 8, this shank is relatively stiff or 85 rigid, particularly in lateral directions. This facilitates insertion of the button through the buttonholes of the collar and neck band and provides the desired rigidity in the shank 90 of the button so that it will hold the ends of the collar and neck band firmly in place.

The spring wire forming the button is 95 preferably relatively heavy, yet, at the same time, the number of turns or convolutions in the stem 6 is preferably sufficiently great so that when the shank is in extended position the amount of separation between each of the respective turns or convolutions in the shank is relatively small. In Figure 5 the 100 amount of separation is exaggerated about

the same amount as are the collar and neck band thicknesses. In use of the button the extension of the shank and the resulting relatively slight spaces thereupon formed between the spring-wire turns of the shank are not formed until the button is inserted through the buttonholes of the collar and neck band. As the button is inserted the turns of the shank are close together and this, together with the relative rigidity or stiffness in the shank of the button, permits insertion with ease and without interference by the extensible character of the shank.

In Figure 4 the button is shown in use at 15 the rear of the neck band of the shirt. The shirt neck band is shown at 18 and has the usual pocket 19 for the base 7 of the button. The collar band is indicated at 20, and the shank 6 of the button extends through the 20 buttonholes 21 and 22 in the neck band 18 and collar band 20, respectively. The springiness in the shank 6 serves to retain the button in its relatively contracted condition and holds the base 7 in close engagement with 25 the neck band 18 and the head 8 in close engagement with the collar band 20, thereby avoiding objectionable protrusion and possible discomfort.

When the button is used at the front of the 30 neck band the shank 6 passes through buttonholes 23, 24, 25 and 26 in the overlapping front ends 27 and 28 of the neck band, and in the overlapping front ends 29 and 30 of the collar band, respectively. The number of 35 thicknesses at this place is greater, and the extensible shank 6 is extended to accommodate the greater number of thicknesses and the springiness tends to contract the shank and thereby holds the base 7 in close engagement with the neck band end 28 and the head 8 in close engagement with the collar band end 30.

I claim:

1. As a new article of manufacture, a collar button, made up of a single piece of spring-wire, coiled at one end to form a base, at the opposite end to form a head and between the base and head to form a coiled extendible and contractable shank, and the 45 head end of the wire being turned down through the interior of the head and extending down within the interior of the shank.

2. As a new article of manufacture, a collar button, made up of a single piece of 50 spring wire, coiled at one end to form a base, at the opposite end to form a head, and between the base and head to form a coiled extendible and contractable shank, and the head being tapered or rounded upwardly at the 55 top and at the bottom coiled in a plane generally parallel the plane of the base.

3. As a new article of manufacture, a collar button, made up of a single piece of 60 spring wire, coiled at one end to form a base, at the opposite end to form a head, and be-

tween the base and head to form a coiled extendible and contractable shank, the head end of the button being coiled out from the shank to a dimension wider than the shank and coiled back toward the center of the 70 head over the top of the part of the head which is coiled out from the shank.

4. As a new article of manufacture, a collar button, having a shank and enlarged end made up of a single piece of spring wire, said wire coiled to form a coiled extendible and contractable shank with the enlarged end formed by coiling the wire out from one end of the shank to a dimension wider than the shank, the wire being coiled back toward the 75 center of said enlarged end from the outer margin and over the top thereof.

In witness whereof, I hereunto subscribe my name this 4th day of January, 1932.
